(No Model.)

J. KINTZ.

EXTENSION CHANDELIER.

No. 321,506.

Patented July 7, 1885.

UNITED STATES PATENT OFFICE.

JOSEPH KINTZ, OF BALLARD VALE, MASSACHUSETTS.

EXTENSION-CHANDELIER.

SPECIFICATION forming part of Letters Patent No. 321,506, dated July 7, 1885.

Application filed October 1, 1884. (No model.)

To all whom it may concern:

Be it known that I, JOSEPH KINTZ, of Ballard Vale, in the county of Essex, of the Commonwealth of Massachusetts, have invented a new and useful Improvement in Extension Chandeliers or Lamp-Holders; and I do hereby declare the same to be described in the following specification and represented in the accompanying drawings, of which—

10 Figure 1 is a front elevation, Fig. 2 a longitudinal section, and Fig. 3 a transverse section, of a chandelier extension-body provided with my invention, the nature of which is defined in the claims hereinafter presented. 15 Figs. 4 and 5 are inner side views of its notched jaws. Fig. 6 is a front view of the actuator of the said jaws.

The extension chandelier or lamp-holder consists of a slotted tube, a rod or tube to 20 slide lengthwise within the said tube, a stud or projection from such rod or tube, two metallic jaws or strips of metal, each having a series of notches of like kind, number, and size in its inner edge, and mechanism for 25 moving such strips or jaws either toward or away from each other in a lateral direction, all being substantially as hereinafter explained, to enable the rod or tube provided with the stud or projection to be slid lengthwise within 30 the outer or slotted tube, and fixed thereto at different distances from its lower end, the outer tube being intended to have fixed to it a series of brackets or arms for supporting candles or lamps, while the inner tube or rod is 35 secured at its upper end to or depends from a ceiling.

In the said drawings, A and B are two tubes, the first of which extends longitudinally within the other. The outer tube, B, has a slot, *a*, 40 in it, which terminates near each end of the tube, and there extends from the inner tube, A, into such slot a stud or the head *b* of a screw, C, that is screwed transversely into the tube.

45 Within the tube B, and partially encompassing the tube A, are two bars, D D, in the edge of each of which—that is, next to the slot *a*—is a series of semicircular notches, *c*, they being arranged at equal distances apart, 50 and those of one bar being directly opposite those of the other. Each notch has a diameter

corresponding to that of the head *b* of the screw C. Each bar D is a long and thin strip of plate metal. It is held within the tube by caps *x* *y* at the ends thereof. Between the 55 said two curved bars is the actuator E, which is another long strip of metal, connected at the lower end to a slider, F, arranged within a tubular neck, G, projecting downward from the tube B, and encompassed by a tubular 60 slider, H, connected to the slider F by a pin, *d*, that extends from one to the other of the two sliders and through a short slot, *e*, made in the tube G lengthwise thereof. The said tube G is closed at its lower end by a cap, *f*, 65 screwed upon it, and there is within the tube a spiral spring, *g*, for advancing the actuator, which is to be retracted by the hand of a person applied to the slider H, and drawing the slider downward in the tube G. The slider F 70 has fixed to it a wedge, I, provided with a stud, *h*, of the width of and extended into the slot *a*. On retracting the slider F its wedge will be drawn between and against two projections, *i i*, of the notched bars D D, and will 75 force the bars apart sufficiently for the tube B to be moved lengthwise upon the tube A. Having so moved the tube A the required distance, the slider F is next to be allowed to be advanced by the spiral spring *g*, which, in so 80 moving the said slider, will cause it to correspondingly move the actuator between the two notched bars. The actuator is provided with triangular cams or projections *k*, extending from its opposite edges into correspondingly- 85 shaped notches *l* in the two bars D D, all being as represented. During an advance of the actuator its cams *k* operate in the notches so as to cause the two bars D to approach each other at their notched edges and close upon 90 the head of the screw C, and thus hold the two tubes A and B locked together, from which it will be seen that the tube A can be moved lengthwise relatively to the tube B and locked to it when adjusted to the proper distance.

The brackets for holding the candles or lamps of the chandelier are to be attached to and project radially from a bowl, L, fixed to and encompassing the outer tube, B.

I claim, in an extension chandelier or lamp-holder—

1. The combination of the tube A, having the stud or headed screw C, and the slotted tube B, with the jaws or strips D D, notched as set forth, and with mechanism for moving such 5 jaws laterally toward and away from each other, to either engage them with or disengage them from the said stud or screw, all being substantially as set forth.

2. The combination, substantially as described, for operating the notched jaws D D within their tube, and so as to engage them with and disengage them from the stud or

screw C, of the rod or tube A, such combination consisting of the neck G, with the spiral spring g, the connected sliders F and H, the wedge I, projections i i, and notches l of the bars D D, and the actuator E, having the cams or projections k k, all being arranged and to operate essentially as represented. 15

JOSEPH KINTZ.
